UNITED STATES PATENT OFFICE.

WALTER A. GUHMAN, OF NEW YORK, N. Y.

PORTABLE LIGHTER.

Application filed December 27, 1922. Serial No. 609,218.

My invention relates to electric lighters of the portable type, and while particularly designed for use in connection with automobiles or the like, may be employed whenever a source of electric energy is available.

The object of my invention is to supply a cheap, lasting and efficient device, by means of which the electric current may be utilized to provide a lighter for the manifold purposes for which a match is usually employed.

A further object of the invention is to furnish my improved device in a small, compact and attractive form, so constructed that it can be easily hung up or mounted in an automobile or elsewhere adapted for its use, and readily placed in circuit for operation.

My invention is described herein as embodied in a casing having pockets, cut away intermediate their ends, for holding the principal elements of my improvement. These consist of a sparker which is placed in one of the pockets, and a vial or receptacle for holding a small amount of inflammable fluid, or some cotton saturated with the same, or both, which tube also serves as a holder for a torch or igniter having means at its inner end for holding a small amount of asbestos fibre or similar material. The sparker is equipped at its ends with the usual terminal means for connection to a source of electricity, and is cut away to form a gap, on each side of which electrodes protrude slightly. When my lighter is ready for operation, the igniter is made to bridge the gap and complete the circuit, which, on being broken, causes a spark to set alight the fibre at the end of the igniter.

Referring to the drawings forming part of this specification, Figure 1 is a front elevation of my complete invention; Figs. 2 and 3 are vertical sections on the lines 2-2 and 3-3, respectively, of Fig. 1, looking in the direction of the arrows; Fig. 4 shows my device connected for operation with the igniter in position preparatory to ignition, and Fig. 5 is a section on the line 5-5 of Figure 4.

In the drawings, in which similar numerals of reference refer to corresponding parts in the different figures, 1 is a casing, made of leather or similar material, provided with two pockets 2 and 3, in which are removably placed a sparker 4 and a vial or receptacle 5, the latter being for the purpose of holding a small amount of gasoline, naphtha, alcohol or similar fluid, or some cotton sat-

urated with the same, as well as for the reception of the torch or igniter 6 for the purpose hereinafter described.

The sparker 4 is about two and one-half inches in length, and is preferably made of porcelain encircling a metal conductor 7. The sparker is cut away at 8, corresponding with the cutaway portion of the casing, and on each side of the gap the ends of the metal conductor forming the electrodes 9 and 10 project slightly. Attached to the bottom electrode 10 is a forked metal rest 11 which enables the igniter to be more easily and certainly placed in position to bridge the gap. The sparker is fitted with the usual terminal screws 12 and leading-in guides 13 for attachment to wires leading to a battery or the like, as diagrammatically illustrated in Fig. 4.

The tube or vial 5 is of the same length as the sparker and is also preferably made of porcelain. In the bottom of this tube is placed a small quantity of cotton or kindred material 14, which is saturated with gasoline or similar fluid, a small amount of the said liquid being also contained therein if desired.

The igniter 6 is adapted for insertion into said vial. This igniter is constructed of metal with the exception of the handle, which I prefer to make of porcelain, although any non-conducting material may be used. The inner end of the igniter is provided with prongs or a claw 15, intended to hold and retain a small quantity of asbestos fibre. The handle of the igniter 6 is designed also to act as a stopper for the mouth of the vial or tube 5, the circular extension 16 closely fitting the said mouth.

The openings 17, 17 in the casing are for the purpose of hanging my device in the place where it is to be used.

From the foregoing description the operation of my device will be obvious. In an automobile, for instance, the lighter is made ready for operation, after being suitably placed, by connecting the terminal of the upper electrode with a wire leading to the magneto generator, spark plug, battery or any source of electric energy, the circuit being completed by connecting the lower terminal with a wire leading to any metal part of the car that will act as a ground. The igniter, with its asbestos-bearing tip saturated with the inflammable fluid, may then be removed from the tube or vial, and its stem placed in

and moved along rest 11 until its inner end contacts with the upper electrode and completes the circuit, which, upon being broken will emit a spark and light the tip.

5 One of the great advantages of my device is its simplicity of structure, and the ease with which it can be mounted in and removed from a car, it being merely a matter of a few moments to engage and disengage the wire 10 connections.

While I have described herein the preferred embodiment of my invention, I do not limit myself thereto, as various changes and modifications may be made therein without 15 departing from the spirit of the invention, and within the scope of the appended claims.

What I claim as new and desire to secure by Letters Patent, is:

1. A portable electric lighter comprising a 20 casing adapted to be attached to the wall of an automobile, two pockets in said casing, both of the pockets cut away intermediate their length, a sparker in one of said pockets with a spark gap which registers with the 25 cutaway portion of the pocket and having terminals adapted to form part of an electric circuit extending through it from each end of the gap, the other of said pockets contain-

ing a receptacle for the reception of inflammable fluid and a removable igniter, prongs 30 on the inner end of said igniter for holding inflammable material, an enlarged collar on the opposite end of said igniter to act as a closure for the pocket containing it, and a forked metal rest at one end of the spark 35 gap, substantially as and for the purpose set forth.

2. In a portable electric lighter, the combination of a casing adapted to be attached to an automobile, two pockets in said casing, 40 both of the pockets being cut away intermediate their length, a sparker in one of said pockets provided with a gap which registers with said cutaway portion and having terminals leading from each end 45 thereof the electrodes of which are located at each end of the pocket, the other of said pockets containing a receptacle for inflammable liquid and a removable igniter which has means at its tip for holding inflammable material, the whole operating substantially as and for the purpose set forth.

In testimony whereof, I have signed my name to this specification.

WALTER A. GUHMAN.
